US00D803227S

(12) **United States Design Patent** (10) Patent No.: **US D803,227 S**
 Thai et al. (45) Date of Patent: ** Nov. 21, 2017

(54) **DISPLAY APPARATUS INCLUDING A COMPUTER GENERATED ICON**

(75) Inventors: **Tom Thai**, New York, NY (US); **John Kilpatrick**, New York, NY (US); **Dejan Sormaz**, Ontario (CA); **Ramon Espinosa**, Brooklyn, NY (US); **David Edward Miller**, Arlington, VA (US); **Karin Jo Eanes**, Bluemont, VA (US)

(73) Assignee: **Oath (Americas) Inc.**, Dulles, VA (US)

(**) Term: **14 Years**

(21) Appl. No.: **29/376,570**

(22) Filed: **Oct. 8, 2010**

(51) LOC (10) Cl. **14-04**

(52) U.S. Cl.

USPC **D14/485**

(58) **Field of Classification Search**

USPC D14/485-495; 715/700-867

(57) **CLAIM**

The ornamental design for a display apparatus including a computer generated icon, as shown and described.

DESCRIPTION

The FIGURE depicts a display apparatus including a computer generated icon.

The broken lines in the drawings illustrate unclaimed portions of the computer generated icon and the unclaimed display apparatus, and form no part of the claimed design.

1 Claim, 1 Drawing Sheet
